ABSTRACT

The invention comprises a digital-to-analog converter having a high degree of resolution. An unregulated voltage source supplies current to a network of binary-weighted resistors through a corresponding plurality of selectively actuated switching circuits. A novel parallel-current voltage regulating circuit is connected to a highly accurate reference voltage and regulates the voltage applied to each binary-weighted resistor, after the operation of the associated switching circuit. An 18-bit converter having an accuracy greater than 4 parts per million has been realized.

DIGITAL-TO-ANALOG CONVERTER

This is a continuation of application Sér. No. 136,957 filed Apr. 23, 1971 and now abandoned, which was a continuation-in-part of application Ser. No. 805,543 filed Mar. 10, 1969 and now abandoned.

BACKGROUND OF THE INVENTION

1. Field of the Invention

This invention relates to a digital-to-analog converter and more particularly to a digital-to-analog converter having a high degree of resolution.

10 2. Description of the Prior Art

A digital-to-analog converter is a device for converting electrical signals in digital form into their analog equivalent. Such converters are widely used as an interface between a digital computer and a utilization device which cannot be directly operated by digital signals. For example, a digital-to-analog converter is used to convert digital signals generated by a computer into analog signals to control a machine tool in a computer-controlled machine-tool operation.

Digital computers are, of course, inherently accurate machines, their accuracy being limited solely by the size of the digital words that can be accommodated in the registers and accumulators of the computer. Double and triple length words may be used for extended precision, in some instances. The commercial digital-to-analog converters which are currently available, however, are not capable of converting digital input signals into their analog equivalent with the same degree of resolution inherently possessed by the digital input signals. Prior art digital-to-analog converters typically comprise a network of binary-weighted resistors connected to a common summing resistor. A series of switches associated with the binary-weighted resistors selectively connect a regulated voltage to each resistor in the network, in accordance with the digits of the binary word to be converted. The correspondingly weighted currents which flow in the binary-weighted resistors are summed in a summing resistor or in a load to produce the desired analog signal.

Digital-to-analog converters of this type suffer from several disadvantages. First, the energizing voltage for the network of binary-weighted resistors must be highly regulated. This is difficult to do because the voltage source must supply a considerable amount of current and must have a relatively high potential, if any reasonable degree of resolution is required. While voltage sources having a high degree of regulation accuracy are commercially available, these sources are accurate only when supplying a constant or slowly varying load. When connected to a rapidly and constantly varying load, as is found for example in a digital-to-analog converter, the regulating accuracy drops to a much lower figure, typically 0.01%. This drop in accuracy is caused by limitations in the regulating circuitry itself as well as uncertainties as to the internal impedance of the voltage source. Furthermore, such a voltage source is relatively expensive and the above-mentioned limitation on the degree of voltage regulation which can be obtained of necessity limits the resolution of prior art digital-to-analog converter to approximately 13 bits. Additionally, in the prior art, the regulation of the energizing voltage source always occurs *before* the source is switched to energize the binary-weighted resistors. Thus, if electromechanical switching devices are used, contact resistance also becomes limiting. On the other

hand, if semiconductor switching is used, the wide manufacturing variations between semiconductors of the same type and the consequent unpredictable voltage drops through the transistors when conducting, are also limiting. The use of field-effect transistors promises to improve this situation slightly, but by not more than one bit, at the very best. Thus, practically speaking, prior art digital-to-analog converters are inherently limited to a resolution of less than 14 bits.

The novel circuitry of the digital-to-analog converter disclosed herein, however, can attain an accuracy and degree of resolution which are both at least one order of magnitude better than that obtained in the prior art. An experimental 18-bit digital-to-analog converter has been constructed and operated. The resolution of this experimental converter is limited only by the state of the art, which at the present time can achieve resistor values and reference voltage sources accurate to one part per million. As the art progresses it will be possible to increase the resolution of digital-to-analog converters constructed according to the principles of this invention as well as those constructed according to the teachings of the prior art, but the novel circuitry disclosed herein is such that the instant digital-to-analog converter will always have an accuracy at least one order of magnitude greater than the prior art.

A preferred embodiment of the invention comprises a network of binary-weighted resistors connected to a summing load. An unregulated voltage source is connected through a corresponding series of switching circuits to each resistor in the network. These switching circuits are selectively energized, in accordance with the digits of the binary number to be converted, and connect the unregulated voltage source to each binary-weighted resistor in the network to thereby generate the analog signal.

An important feature of the invention is the highly accurate regulation of the unregulated energizing voltage *after* this unregulated voltage has been switched to energize each binary-weighted resistor. This regulation is accomplished by a novel parallel-current voltage regulating circuit comprising a highly accurate source of reference potential, and an operational amplifier having a feedback loop connected to supply a compensatory regulating current to the resistor, in parallel with the current supplied by the unregulated source, thereby maintaining the potential developed across the binary-weighted resistor equal to the potential of the reference voltage.

An alternate embodiment of the invention uses a difference amplifier instead of an operational amplifier in the parallel-current voltage regulation circuit. This substitution simplifies the circuitry to such an extent that the components for a low precision, high speed digital-to-analog converter having, for example, a six-bit digital input, may be incorporated on a single monolithic circuit chip. Six-bit converters implemented on single circuit chips exist in the prior art, however, these converters do not use parallel-current voltage regulation *after* switching. Typical prior art circuits require an operational amplifier in the output circuit to provide a reasonable output voltage swing, but this limits the settling time of the circuit. Such an operational amplifier is not needed in the output circuit of a digital-to-analog converter which, according to the present invention, uses parallel-current voltage regulation; and which,

therefore, can be built to exhibit a much faster settling time.

DESCRIPTION OF THE PREFERRED EMBODIMENT

FIG. 1a is a schematic drawing of a 3-bit digital-to-analog converter which is typical of the prior art. In this converter a ladder network of three binary-weighted resistors, R , $2R$ and $4R$, is connected at one end via a summing resistor R_s to ground. Switches S_1 , S_2 and S_3 represent electromechanical switching devices which can selectively connect the free end of any of the binary-weighted resistors either to ground or to a common reference voltage $+E_{ref}$. The switches S_1 through S_3 are shown in their normal, or open, position and in that position the switches connect ground to each of the binary-weighted resistors. When operated, however, each of the switches S_1 through S_3 applies the potential $+E_{ref}$ to the associated binary-weighted resistor causing current flow therethrough. The output voltage, E_o , developed across the summing resistor R_s may be calculated by taking the ratio of resistor R_s and all binary-weighted resistors in parallel with it to the sum of that quantity just calculated and the parallel combination of all binary-weighted resistors connected through operated switches to the reference source. Because the binary-weighted resistors have resistance values which increase according to the powers of 2, the output voltage E_o will increase linearly when switches S_1 through S_3 are selectively closed in binary order.

FIG. 1b illustrates the operation of the converter in FIG. 1a and shows the condition of switches S_1 through S_3 for various combinations of input signals as well as the output voltage E_o developed across the summing

resistor R_s for each combination. This table assumes that $R_s = R$. If desired, the circuitry can be arranged so that switches S_1 through S_3 switch the binary-weighted resistors between $-E_{ref}$ and $+E_{ref}$ rather than ground and $+E_{ref}$; however, the linear relationship between the analog output E_o and the binary input will not be affected. In this latter case the graph of E_o versus the binary input would be shifted downward and would pass through the $E_o = 0$ point between the binary input numbers 011 and 100 rather than at the normal 000 point. This type of arrangement is used, for example, if the analog signal is to be used to control the deflection of an electron beam and it is desired that the rest position of the beam be at the center of the cathode ray screen.

By increasing the number of binary-weighted resistors in FIG. 1a, it is possible to increase the resolution of such a converter. However, as discussed previously, if more than 12 or 13 binary-weighted resistors are connected to the converter, the change in output voltage E_o across summing resistor R_s as the last switch, corresponding to the least significant digit of the binary number to be converted, is operated, is so small that the reference voltage source E_{ref} must be exceedingly well regulated. This is necessary so that no voltage perturbations will occur in E_{ref} which even approach in magnitude the voltage change across R_s due to a change in the least significant digit of the binary number.

The cost and difficulty of regulating a power supply for use with a digital-to-analog converter having more than 13 bits has already been discussed. The contact resistance of electromechanical switches S_1 through S_n must also be less than the change in resistance which occurs as the last binary-weighted resistor is switched in and out of the circuit. This, too, limits the resolution of the digital-to-analog converter shown in FIG. 1a.

As previously discussed, this problem can be alleviated somewhat by the use of semiconductor switches. FIG. 2 is a schematic diagram of a portion of a commercially available 13-bit digital-to-analog converter which uses semiconductor switching elements. Referring to FIG. 2, when transistor T_5 is turned "On" by the application of a binary "one" signal to the base of transistor T_1 , the voltage from source $-E_{ref}$ is applied to the binary-weighted resistor $2R$, as shown. Similarly, the application of a binary "zero" signal to the base of transistor T_1 turns transistor T_5 "Off" and transistor T_4 On thus connecting a ground to binary-weighted resistor $2R$. The alternate operation of transistors T_4 and T_5 is analogous to the operation of one of the electromechanical switches in FIG. 1a. Obviously, the use of transistors in lieu of electromechanical switches eliminates the contact resistance problem but introduces yet another problem in its place. As is well known, when a semiconductor switching device is turned heavily On, it simulates a short circuit in that the resistance of the emitter-collector path is very low. There is, nevertheless, a finite voltage drop across a conducting transistor and this voltage drop must be taken into account in a high resolution digital-to-analog converter. At this time, it is still not possible to manufacture transistors accurately enough so that the collector-emitter voltage drop in the On condition is uniform from sample to sample. Thus, difficulty is experienced in calibrating the various stages of a digital-to-analog converter which uses transistorized switching and if a transistor fails and must be replaced, the entire converter must be

recalibrated, as each stage interacts with every other stage. Thus, while the use of transistorized switching circuits, particularly field-effect transistors, may increase the resolution of prior art converters by one or possibly two bits, the limitation imposed by the inability to accurately regulate the reference voltage source after switching occurs are still limiting.

The instant invention successfully eliminates the aforementioned problems and provides a digital-to-analog converter which is significantly superior to anything heretofore attainable. This superiority is attained by the novel concept of regulating an unregulated voltage source *after* it has been switched to generate current flow in a binary-weighted resistor and by using a unique parallel-current voltage regulating circuit to maintain this regulation to a very high degree of accuracy.

FIG. 3a depicts one embodiment of the parallel-current voltage regulating circuit utilized in the instant digital-to-analog converter. Referring to the drawing, a circuit 11 supplies a reference voltage from an external voltage source 12 which may advantageously comprise a standard cell having an open-circuit voltage E_r and an internal impedance R_r . The standard cell, whose voltage must be accurately known, for example, to at least one part per million, is maintained at a constant temperature by the use of an oven. The circuit 11 connects the reference voltage source 12 to the input 13 of an operational amplifier 14 via a resistor R_2 . The other input of operational amplifier 14 is grounded. In the experimental digital-to-analog converter actually constructed and operated, a commercially available Analog Devices Model 211 operational amplifier was used. This amplifier has a gain of $A = 10^8$, an input resistance of 0.5 megohms, an output resistance of essentially 0 ohms, and a noise factor of 10 microvolts r.m.s. Obviously one skilled in the art could substitute other types of operational amplifiers for the one used in the experimental embodiment provided that the characteristics are similar. The output 15 of operational amplifier 14 is connected by a feedback loop 16 to the input 13 thereof. An output resistor R_0 and a resistor R_1 are connected in the feedback loop. R_L , the load resistor to be energized, is connected between ground and the juncture of resistors R_1 and R_0 in feedback loop 16. A second circuit 18 connects an unregulated voltage from an external voltage source 19 to the juncture 17 of resistors R_1 and R_0 via a resistor R_4 . The unregulated voltage source 19 advantageously comprises any suitable source having a voltage E_s and an internal impedance R_s .

In operation, the unregulated voltage source 19 supplies a current through R_4 and R_L to ground, and the voltage E_s which is developed across load resistor R_L at juncture 17 is regulated so that it equals the open circuit voltage E_r of reference voltage source 12 to a high degree of accuracy, regardless of wide variations in the magnitude of the voltage from unregulated voltage source 19. If, as in the illustrative embodiment, the potential of reference source 12 is known to within 1 part per million then resistors R_1 , R_2 and R_L must also be accurate to within one part per million or better.

Assume that unregulated voltage source 19 is supplying a current i_a to load resistor R_L and that the voltage developed across juncture 17 is E_s . The potential of unregulated voltage source 19 is "seen" by the input of operational amplifier 14 through resistors R_4 and R_1 , R_1

being in feedback loop 16. Input 13 of operational amplifier 14 also sees the potential from reference voltage source 12 through resistor R_2 . In order that the operational amplifier will regulate over the desired range, the magnitude of resistors R_2 and R_1 are selected such that R_1 is approximately equivalent to the series combination of R_2 and the internal resistance R_r of reference voltage source 12. Typically, R_r is negligibly small and, thus in practice, R_2 will equal R_1 . If the potential of unregulated voltage source 19 should vary for any reason, the magnitude of voltage E_s will also tend to vary. This variation is sensed at the input of operational amplifier 14 and an output current is generated in feedback loop 16. A fraction, i_b , of this current will flow through load resistor R_L . Since i_b is in parallel with i_a the current supplied from feedback loop 16 will tend to alter the magnitude of E_s in an offsetting manner, and maintain E_s equal to the voltage of reference voltage source 12. For this to occur, it is necessary that the magnitude of resistor R_4 be selected so that its resistance, together with the internal impedance R_s of unregulated voltage source 19, approximately equals the resistance of load resistor R_L . Load resistor R_L will, of course, vary in resistance for each stage of the digital-to-analog converter.

A mathematical analysis of this circuit is set forth below and this analysis proves that the parallel-current voltage regulating circuit shown in FIG. 3 does indeed maintain the voltage E_s developed across load resistor R_L equal to the voltage of reference voltage source 12.

FIG. 4a shows the circuit of FIG. 3a redrawn in simplified form. The internal resistance R_r of reference voltage source 12 and the internal resistance R_s of unregulated voltage source 19 have been ignored, as typically they are very small compared to R_2 and R_4 , respectively. If they are not small compared to R_2 and R_3 , the following mathematical analysis is still valid provided that R_2^{-1} and R_4^{-1} are substituted in the following proof where

$$R_2^{-1} = R_2 + R_r \quad (1)$$

$$\text{and} \quad R_4^{-1} = R_4 + R_s \quad (2)$$

FIG. 4a itself may be further simplified, as shown in FIG. 4b, by defining two new quantities R_T and E_T where

$$R_T = R_4 R_L / (R_4 + R_L) \quad (3)$$

$$\text{and} \quad E_T = R_L / (R_4 + R_L) \cdot E_r \quad (4)$$

Assume that currents i_1 , i_2 and i_3 flow as shown in FIG. 4b. No current is shown flowing into the operational amplifier as it normally requires no input current.

Now the currents i_1 , i_2 and i_3 may be found from the following equations.

$$i_1 = (E_r - E_s) / (R_1 + R_2) \quad (5)$$

$$i_2 = (E_0 - E_s) / R_0 \quad (6)$$

$$\text{and} \quad i_3 = (E_s - E_T) / R_T \quad (7)$$

$$\text{But } E_0 = -A E_t \quad (8)$$

and

$$E_i = R_1/(R_1 + R_2) \cdot (E_r - E_s) + E_s \quad (9)$$

$$= R_1/(R_1 + R_2) \cdot E_r \cdot 30 \cdot [R_2/(R_1 + R_2)] \cdot E_s \quad (10)$$

$$\text{Now } i_1 + i_2 = i_3 \quad (11)$$

Therefore, from Equations 5, 6, 7 and 11

$$(E_r - E_s)/(R_1 + R_2) + (E_o - E_s)/R_o = (E_s - E_T)/R_T \quad (12)$$

and from Equations 8 and 10

$$E_o = -A \cdot R_1/(R_1 + R_2) \cdot E_r - A \cdot R_2/(R_1 + R_2) \cdot E_s \quad (13)$$

From Equations 12 and 13, we obtain

$$[(E_r - E_s)/(R_1 + R_2)] - [A \cdot R_1 \cdot E_r/R_o(R_1 + R_2)] - [(A \cdot R_2 \cdot E_s/R_o(R_1 + R_2)) - (E_s/R_o)] = (E_s - E_T)/R_T \quad (14)$$

Simplifying this expression we get:

$$E_r \cdot [1/(R_1 + R_2)] - [A \cdot R_1/R_o(R_1 + R_2)] + E_T/R_T = E_s \cdot 1/R_T + 1/R_o + [1/(R_1 + R_2)] + A \cdot R_2/R_o(R_1 + R_2) \quad (15)$$

Thus

$$[E_r/(R_1 + R_2)] \cdot [1 - A \cdot R_1/R_o] + E_T/R_T \cdot 1[(R_1 + R_2)/(R_1 + R_2)] = [E_s/(R_1 + R_2)] \cdot [(R_o + R_T)(R_1 + R_2)/R_o R_T] + 1 + A \cdot R_2/R_o \quad (16)$$

Simplifying we get

$$E_r (R_o R_T - A R_1 R_T) + E_T (R_1 + R_2) R_o = E_s [(R_o + R_T)(R_1 + R_2) + R_o R_T + A R_2 R_T] \quad (17)$$

Therefore

$$E_s = E_r (R_o R_T - A R_1 R_T) / [(R_o + R_T)(R_1 + R_2) + R_o R_T + A R_1 R_T] + E_T (R_1 + R_2) R / [(R_o + R_T)(R_1 + R_2) + R_o R_T + A R_1 R_T] \quad (18)$$

Now from Equation 3

$$R_T = R_4 R_L / (R_4 + R_L) \quad (19)$$

and

$$R_4 \text{ typical} \approx 300 \text{ ohms}$$

$$R_L \text{ typical} \approx 500 \text{ ohms}$$

Thus

$$R_T \text{ typical} \approx (300 \times 500)/800 = 200 \text{ ohms}$$

Further, in a typical digital-to-analog converter stage

$$R_0 \text{ typical} \approx 500 \text{ ohms}$$

$$R_1 \text{ typical} \approx 10,000 \text{ ohms}$$

$$R_2 \text{ typical} \approx 10,000 \text{ ohms}$$

and

$$A_{\text{typical}} \approx 10^8$$

Substituting these values into Equation 18, we get

$$E_s = \frac{E \nabla [(500)(200) - (10^8)(10,000)(200)]}{[(700)(20,000) + (100,000) + (10^8)(10,000)(200)]}$$

$$+ \frac{E_T(20,000)(500)}{[(700)(20,000) + (100,000) + (10^8)(10,000)(200)]}$$

$$E_s = \frac{E_r[10 - (200)(10^8)]}{[1400 + 10 + 200(10^8)]} + \frac{E_T(100)}{140 + 1 + 20 + 10^8} \quad (15)$$

Therefore

$$E_s \approx [-E_r(10^8)/(10^8)] + E_T/(10^7)$$

or

$$E_s \approx -E_r + (E_T/10^7)$$

Ignoring this latter term, which is exceedingly small, we get $E_s = -E_r$ and the effect of E_T (and thus E_r) upon E_s may be ignored.

Another important feature of the parallel-current voltage regulating circuit shown in FIG. 3a is its excellent response to transient switching pulses. An experimental regulator, constructed in accordance with this invention, was found to have a settling time of less than one microsecond. This figure is suitable for virtually all applications which require a digital-to-analog converter of this degree of resolution.

FIG. 3b shows a modified version of the circuit disclosed in FIG. 3a. In FIG. 3b a diode 21 is connected between output lead 15 and input 13 and poled so that if the output voltage E_o of operational amplifier 14 goes positive, diode 21 conducts shorting out the operational amplifier 14. Obviously, diode 21 could be poled in the opposite direction if it is desired to short-out operational amplifier 14 when the output voltage goes negative.

It is possible to improve still further the parallel-current voltage regulating circuit shown in FIG. 3a. As shown in FIG. 5, this is accomplished by substituting for the external reference voltage source 12 in FIG. 3a, an unregulated voltage source which itself has been regulated by a parallel-current voltage regulating circuit of the type disclosed in FIG. 3a. This process may be repeated over and over again although practical considerations make the use of more than two parallel-current voltage regulating circuits in "tandem" of doubtful value. Referring now to FIG. 5, a circuit 11¹ connects a reference voltage source 12¹ to a resistor R_2^1 thence to the input 13¹ of an operational amplifier 14¹. A feedback loop 16¹ which includes an output resistor R_o^1 and a resistor R_1^1 connects the output 15¹ of operational amplifier 14¹ to the input 16¹. A load resistor R_L^1 is connected to the juncture 17¹ of resistors R_o^1 and R_1^1 and is supplied with current from an external unregulated source 19¹ through a resistor R_4^1 .

The operation of the portion of the circuit disclosed in FIG. 5 described so far is identical with that described for FIG. 3a and will not be repeated here. Suffice it to say that the voltage E_s^1 developed across load resistor R_L^1 is held to the voltage of reference source 12¹. Importantly, no significant current is drawn from the standard cell in reference source 12¹.

The regulated voltage E_s^1 developed across resistor R_L^1 is next connected via circuit 11 and resistor R_2 to the input of a second operational amplifier 14 and the remainder of its circuit and the operation thereof is identical to that described with reference to FIG. 3a. The circuit of FIG. 5 accomplishes the substitution of E_s^1 , the voltage developed across resistor R_L^1 , for the reference voltage source 12 normally used. Unlike a standard cell, however, the circuit arrangement of FIG. 5 can supply significant current from the new reference source E_s^1 which increases the range and accuracy of overall regulation.

FIG. 6 shows a preferred embodiment of a digital-to-analog converter according to the invention. With the exception of minor changes in the resistance of some components caused by a corresponding change in the resistance of the associated binary-weighted resistor, each stage of the converter is identical, thus only the first is illustrated and described in detail.

As discussed in connection with FIG. 2, in the preferred embodiment, the potential applied to the various binary-weighted resistors in the ladder network is switched between $+E_r$ and $-E_r$. However, it will be appreciated that the circuitry disclosed is equally suitable for switching between $\pm E_r$ and ground, should this be desired. If this were done, it would, of course, be necessary to regulate the ground potential, as well as the supply source, if a high degree of resolution is required.

In FIG. 6 a network 101 comprises a plurality of binary-weighted resistors $R, 2R, 4R, \dots, 2^{n-1}R$ connected at one end. Network 101 is connected by a lead 102, to an external load 103 which, in the preferred embodiment shown, is the deflection coil of an electron-beam deflection device. The series combination of load 103 and one of the binary-weighted resistors corresponds to load resistor R_L in FIG. 3a. It will be appreciated, however, that load 103 may be any external load capable of working with the digital-to-analog converter disclosed.

Input 104₁ is connected by leads 106a and 106b to essentially identical upper and lower halves of the first stage of the converter. Again, for simplicity, only the upper half of the first stage will be discussed in detail, although both are illustrated. The circuitry and operation of the lower half is entirely analogous to the operation of the upper half, provided, of course, that appropriate corrections are made for the change in polarity of the supply source.

Returning now to the input 104₁, lead 106a connects the input via a resistor 107a and a capacitor 108a to the base of transistor Q1a. Resistor 109a connects biasing potential from source $-E_r$ to the base of transistor Q1a. The emitter of transistor Q1a is connected to a second biasing potential $-E_B$ via a lead 111a. The collector of transistor Q1a is connected via a resistor 112a and a capacitor 113a to the base of transistor Q2a. A biasing resistor 114a connects the base of transistor Q2a to its emitter and thence via a lead 116a to an unregulated voltage source $+E_r$. The collector of transistor Q2a is connected by a resistor 117a to a feedback loop 118a, a junction 119₁ and the first binary-weighted resistor R.

The concept of regulating the energizing voltage sources $+E_r$ and $-E_r$ after they have been selectively switched to energize the binary-weighted resistors in ladder network 101 has been previously discussed. To accomplish this regulation, after switching, an operational amplifier 121a having an input 122a and an out-

put 123a is connected via an output resistor 124a and the serial connection of a diode 126a and a Zener-diode 127a to feedback loop 118a. A resistor 128a connects the junction 129a of feedback loop 118a and a resistor 117a to one end of a trimmer resistor 130a and via the slider arm thereof to input 122a. The other end of trimmer resistor 130a is connected via a resistor 125a to an external reference voltage $-E_{ref}$. The output 123a of operational amplifier 121a is also connected via a pair of diodes 131a and 132a to the input 122a thereof. A resistor 133a connects the midpoint of diodes 131a and 132a to ground.

As previously discussed, the lower half of the first converter stage is essentially identical to the upper half just described. However, it will be noted that the polarity of transistors Q1a and Q1b and Q2a and Q2b are reversed. Similarly, lead 111b connects the emitter of transistor Q1b to ground rather than to the biasing voltage $-E_B$ and resistor 109b connects the base of transistor Q1b to the biasing potential $+E_r$ rather than $-E_r$. Similarly, lead 116b connects the emitter of transistor Q2b to $-E_r$ rather than $+E_r$ and the polarity of diodes 126b, 131b, 132b and Zener diode 127b are also reversed.

In operation, assume that a very low potential, illustratively zero volts, is applied to input 104₁ and is indicative of a binary "one" input to the first stage of the converter. Because the emitter of transistor Q1b is grounded, when zero volts is applied to the base thereof there will be, of course, zero volts on the base-emitter junction of transistor Q1b. Thus, the large positive potential $+E_r$ which is applied to the base of transistor Q1b via biasing resistor 109b maintains transistor Q1b positively turned On. This in turn keeps transistor Q2b Off which inhibits the application of the $-E_r$ voltage present on lead 116b to the junction point 119₁ and binary-weighted resistor R.

Resistors 107a and 107b prevent transistors Q1a and Q1b from loading down the input signal on input 104₁ and capacitors 108a and 108b are provided to speed-up the transient response of transistors Q1a and Q1b. The zero potential which is applied, via lead 106a, to the base of transistor Q1a turns transistor Q1a heavily On, by virtue of the negative potential $-E_B$ connected to the emitter thereof by lead 111a. The resistor 109a which connects the base of transistor Q1a to biasing source $-E_r$ plays no part in the operation of the circuit at this time. This connection is provided to ensure that transistor Q1a is positively turned Off when the input on lead 104₁ corresponds to a binary "zero" and transistors Q1b and Q2b are conducting.

When transistor Q1a is turned On the potential at the collector thereof becomes approximately equal to the negative potential $-E_B$ which is present on its emitter. The base of transistor Q2a on the other hand, is maintained positive because of the positive potential $+E_r$ present on its emitter via lead 116a. Current therefore flows down through current-limiting resistor 112a into the now conducting transistor Q1a and this downward current flow draws current from the base of transistor Q2a and turns transistor Q2a heavily On permitting current to flow from source $+E_r$ through resistor 117a to junction 119₁ and the first binary-weighted resistor R, thence via summing circuit 102 to the load 103.

The value of resistor 112a is selected to limit the current flow through transistor Q1a to a reasonable figure

and capacitor 113a is provided to speed-up the transient response of transistors Q1a and Q2a.

As previously discussed with reference to FIG. 3a, the potential at junction 129a is regulated by means of operational amplifier 121a and feedback loop 118a so that the voltage at junction 129a is maintained equal to the potential of reference voltage $-E_{ref}$. Trimmer resistor 130a, which is typically a 20-turn wire wound potentiometer of approximately 1 ohm resistance, is provided for alignment purposes so that the potential at input 122a to operational amplifier 121a is maintained at zero volts.

Also as previously discussed in connection with FIG. 3a, if for some reason the potential at junction 129a should vary from the reference potential $-E_{ref}$, a compensating, parallel current is supplied to junction 119₁ and binary resistor R from feedback loop 118a to maintain the voltage at junction 129a and hence junction 119₁ constant. The Zener diode 127a, which is connected in the feedback loop 118a, is provided to increase the range of regulation and this diode drops approximately 75% of the voltage difference between the output of operational amplifier 121a, which is typically -5 volts, and the potential at junction 119₁, which is typically +15 volts; the remaining 5 volts being dropped across resistor 124a. Diode 126a is provided to block leakage current from operational amplifier 121a when current is being supplied to resistor R by the lower half of the circuit, which, of course, only occurs when a binary zero signal is present at input 104₁. Diodes 131a and 132a and resistor 133a are connected across operational amplifier 121a to short it out in this latter condition when operational amplifier 121b is functioning.

The operation of the circuit when a binary zero signal is applied to input 104₁ is entirely analogous. The potential applied to input 104₁ in that case is typically -3 volts, thus the biasing potential $-E_r$ applied to the base of transistor Q1a will turn Q1a Off which, in turn, will turn transistor Q2a Off disconnecting the positive source $+E_r$ from junction 119₁ and binary-weighted resistor R. The -3 volt potential applied at input 104₁ is passed to the base of transistor Q1b via lead 106b and, by virtue of the ground present on the emitter of transistor Q1b from lead 111b, turns transistor Q1b On. This, in turn, turns Q2b On passing the $-E_r$ potential on lead 116b to junction 119₁ and binary-weighted resistor R, thence via summing circuit 102 to the load 103 as before. Operational amplifier 121b and feedback loop 118b act to maintain the potential at junction 129b equal to the potential $+E_{ref}$ applied to the input of operational amplifier 121b, in a manner entirely analogous to the operation of the upper half of the circuit.

As previously discussed, under this condition, operational amplifier 121a will be shorted by diodes 132a and 131a and diode 126a will prevent any leakage to junction 119₁ from the upper half of the circuit.

The converter stage which has been illustrated and discussed in detail in the most significant stage in the converter. The stages which correspond to the lesser significant digits of the number to be converted are essentially identical except for minor changes in resistance values, etc. Thus, the application of input signals to input circuits 104₂ through 104₂ and the operation of switching circuits 30_{2(a)} through 30_{n(a)} and 30_{2(b)} through 30_{n(b)} as well as parallel-current voltage regu-

lating circuits 40_{2(a)} through 40_{n(a)} and 40_{2(b)} through 40_{n(b)} need not be discussed in detail.

It is essential, in the first stage of the converter, that resistors 125a, 125b, 128a, 128b as well as binary-weighted resistor R be as accurate as the potential of the reference voltages $+E_{ref}$ and $-E_{ref}$. In the illustrative embodiment of the invention actually constructed, these potentials were known to within 1 part per million. In succeeding less-significant stages of the converter, these tolerances may be reduced, for example, to 2 parts per million, 4 parts per million, 8 parts per million, etc. As previously discussed, the reference voltages $+E_{ref}$ and $-E_{ref}$ are advantageously obtained from a standard cell. The standard cell is advantageously maintained in a controlled environment in a temperature controlled oven. It may also be advantageous, under some circumstances, to maintain resistors 125a, 125b, 128a and 128b and the binary-weighted resistors in a temperature controlled oven, although this has not been found necessary in the experimental 18-bit digital-to-analog converter actually constructed. One advantage of switching the binary-weighted resistors between $+E_r$ and $-E_r$ rather than $+E_r$ and ground is that there is always a current in the binary-weighted resistors, regardless of the input signals to the various stages. Thus, the binary-weighted resistors are subject to constant i^2R heating and, therefore, less likely to alter their resistance value, which would, of course, affect the accuracy of the digital-to-analog conversion.

FIG. 7 shows an alternate embodiment of the digital-to-analog converter, according to this invention, in which difference amplifiers are substituted for operational amplifiers 121a and 121b, shown in FIG. 6, and in which certain changes are made in the switching circuits. The 6-bit converter shown in FIG. 7 encompasses a number of components which may be fabricated on a single monolithic circuit chip, using presently available technology. However, it will be apparent to the practitioner that converters with more than six input bits could be built on a plurality of monolithic chips, or on a single larger chip, if fabrication technology permits. Converters with less than 6 input bits may also be constructed.

In FIG. 7, certain elements are numbered identically to like elements in FIG. 6, as the overall operation of the circuit in FIG. 7 is similar to the operation of the circuit in FIG. 6. However, switching circuits 30 and parallel-current voltage regulation circuits 40 in the schematic of FIG. 7 are different from like elements in the circuit of FIG. 6. These differences will become evident from the description of FIG. 7 which follows.

Referring now to FIG. 7, simplifications have been made in switching circuits 30 to eliminate capacitors and to reduce the number of resistors. Switching circuits 30 are now shown for operation with an input signal having either a positive voltage level, typically +3 volts, or ground as its two input states. Such an input signal is compatible with the positive signal levels currently used in systems using monolithic circuits. However, the modifications necessary to permit switching circuits 30 to operate with negative-going or bipolar input signals would be apparent to the skilled practitioner.

As in the previous description, only the upper half of the most significant stage of the converter will be described in detail. Input 104₁ is connected by lead 106a to the base of transistor Q1a. The emitter of transistor

Q1a is connected through resistor 140a to ground. The collector of transistor Q1a is connected by lead 141a to the base of transistor Q2a. Biasing resistor 114a connects the base of transistor Q2a to its emitter, which is also connected to unregulated voltage source +E_r. The collector of transistor Q2a is connected through resistor 117a to leads 142a and 143a. Lead 142a connects to point 119₁, and binary-weighted resistor R which further connects to summing circuit 102, and load 103. Lead 143a connects through resistor 144a to the base of transistor Q3a, and through diode 146a to the collector of transistor Q3a. The base of transistor Q3a is also connected to ground through resistor 145a. Diode 147a is connected between the emitter and base of transistor Q3a. The emitters of transistors Q3a and Q4a are connected together, and to ground through resistor 148a. The base of transistor Q4a is connected to reference voltage +E_{ref}, and the collector of transistor Q4a is connected to unregulated voltage source +E_r.

As previously stated, the lower half of the first stage is essentially identical to the upper half just described. However, it will be noted that transistors Q1b, Q2b, Q3b and Q4b in the lower half are of opposite polarity compared to their counterparts Q1a, Q2a, Q3a, and Q4a in the upper half. Also, the emitter of transistor Q2b and the collector of transistor Q4b connect to an unregulated voltage source -E_r rather than +E_r. Similarly, the base of transistor Q4b is connected to reference voltage -E_{ref} rather than +E_{ref}. The emitter of transistor Q1b is connected through resistor 140b to biasing voltage source +E_b rather than ground. The magnitude of +E_b is chosen so that during the application of a positive voltage level on input 104₁, transistor Q1b will be turned Off, and during the application of a ground or zero voltage level on input 104, transistor Q1b will be turned On. Diodes 146b and 147b in the lower half are reversed with respect to their counterparts in the upper half.

In operation, assume that a positive voltage level appears on input 104₁, which is indicative of a binary one input to the first stage of the converter. Transistor Q1b will be turned Off by this positive voltage level. This in turn maintains transistor Q2b Off which inhibits the application of voltage -E_r to junction point 119, and binary-weighted resistor R.

The positive voltage level on input 104₁ is applied via lead 106a to the base of transistor Q1a. Since the emitter of transistor Q1a is connected through resistor 140a to ground, a current will flow through the emitter-base junction of transistor Q1a. This emitter-base current turns transistor Q1a On.

When transistor Q1a is turned On, current flows from source +E_r through resistor 114a, the collector of Q1a, and resistor 140a to ground. Resistor 140a limits the magnitude of this current. The resulting voltage drop across resistor 114a causes current to flow through the emitter-base junction of transistor Q2a, turning transistor Q2a heavily On, permitting current to flow from source +E_r through resistor 117a to junction 119, and binary-weighted resistor R to summing circuit 102 and load 103.

The potential at junction 129a is regulated by means of the difference amplifier comprising parallel-current voltage regulation circuit (40₁)a so that the voltage at junction 192a is maintained constant with respect to reference voltage +E_{ref}. Typically, +E_{ref} will be half the magnitude of the voltage to be maintained at junction

129a. Resistors 144a and 145a are chosen so that the voltage appearing on the base of transistor Q3a will also be approximately half the voltage at junction 129a. The voltage on the emitters of transistors Q3a and Q4a will be maintained at slightly less than +E_{ref} by transistor Q4a. If the voltage at junction 129a increases for any reason, the voltage on the base of transistor Q3a will also increase momentarily, causing increased current to flow through the emitter-base junction of Q3a. This increased emitter-base current in transistor Q3a causes a corresponding increase in collector current, which flows from junction 129a through diode 146a. This increased collector current must be drawn through resistor 117a, causing a larger voltage drop thereacross, decreasing the voltage at junction 129a. The converse action results if the voltage at junction 129a decreases for any reason. It can be seen, therefore, that the difference amplifier comprising regulation circuit (40₁)a regulates the voltage at point 129a by varying the current flowing in lead 143a, resulting in parallel-current voltage regulation.

Diodes 146a and 147a are provided to protect transistor Q3a when junction 129 is at the negative potential which results when a binary zero appears at input 104. Diode 146a protects the collector-base junction of Q3a, and diode 147a protects the emitter-base junction of transistor Q3a when junction 129a becomes negative.

The operation of the circuit when a binary zero signal is applied to input 104₁ is analogous to the operation described above for a binary one. The potential applied to input 104₁ to represent a binary zero is typically close to zero volts, or ground potential, which thereby turns transistor Q1a Off and transistor Q1b On. Transistor Q2b is thereupon turned On, passing the -E_r potential through resistor 117b to point 119₁, resistor R, summing circuit 102, and load 103. Parallel-current voltage regulation circuit (40₁)b maintains the voltage at junction 129b at the correct negative potential in a manner entirely analogous to the action of regulation circuit (40₁)a described above.

The operation of the other stages in the converter shown in FIG. 7 is identical to the operation of the most significant stage described above, and need not be described in detail.

It can be seen that the operation of the alternate embodiment digital-to-analog converter, using difference amplifiers to perform parallel-current voltage regulation, is similar to the operation of the preferred embodiment using operational amplifiers for regulation. However, the alternate embodiment typically cannot provide the same degree of precision as the preferred embodiment. As previously mentioned, the preferred embodiment is capable of operation in configurations of up to 18 bits having a conversion accuracy of 4 parts per million. The alternate embodiment converter is intended for use in applications needing fewer bits, typically 6; and lower conversion accuracies, typically 1 part per thousand. The advantage of the alternate embodiment converter, however, which distinguishes it from prior art converters, is its faster conversion time.

While there has been shown and described the novel features of the invention according to a preferred embodiment and an alternate embodiment, it will be understood that various omissions and substitutions in the circuitry illustrated and in its operation may be made

by those skilled in the art without departing from the spirit of the invention.

What is claimed is:

1. In a digital-to-analog converter of the type including a plurality of binary-weighted resistors each having a first terminal connected to a common load and a second terminal selectively connectable by either a first switching circuit to a source of positive energizing voltage or a second switching circuit to a source of negative energizing voltage, the improvement comprising for each binary-weighted resistor:

first means for comparing the voltage at the second terminal with voltage from a first external reference source;

means for supplying a first current to the second terminal and, responsive to the first comparing means, for varying the first current to maintain the voltage at the second terminal substantially constant regardless of variations in the voltage of the positive energizing source;

second means for comparing the voltage at the second terminal with a voltage from a second external reference source; and

means for supplying a second current to the second terminal and, responsive to the second comparing means, for varying the second current to maintain the voltage at the second terminal substantially constant regardless of variations in the voltage of the negative energizing source; wherein

the first external reference source is positive; the second external reference source is negative; the combination of the first comparing means and the first supplying and varying means comprises:

a first difference amplifier having a sensing input, a reference input connected to the first external reference source, and an output;

a first circuit connected between the sensing input of the first difference amplifier and the second terminal of the binary-weighted resistor; and

a second circuit connected between the output of the first difference amplifier and the second terminal of the binary-weighted resistor; and

the combination of the second comparing means and the second supplying and varying means comprises:

a second difference amplifier having a sensing input, a reference input connected to the second external reference source, and an output;

a third circuit connected between the sensing input of the second difference amplifier and the second terminal of the binary-weighted resistor; and

a second circuit connected between the output of the second difference amplifier and the second terminal of the binary-weighted resistor.

2. A digital-to-analog converter according to claim 1, wherein said first and second switching circuits each include a resistor having a value chosen so that the sum of the resistance of each switching circuit and the internal resistance of each corresponding energizing voltage source substantially equals the resistance of said binary-weighted resistor.

3. In a digital-to-analog converter of the type including a plurality of binary-weighted resistors each having a first terminal connected to a common load and a second terminal selectively connectable by either a first switching circuit to a source of positive energizing voltage or a second switching circuit to a source of negative

energizing voltage, the improvement comprising, for each binary-weighted resistor:

first means for comparing the voltage at the second terminal with voltage from a first external reference source;

means for supplying a first current to the second terminal and, responsive to the first comparing means, for varying the first current to maintain the voltage at the second terminal substantially constant regardless of variations in the voltage of the positive energizing source;

second means for comparing the voltage at the second terminal with a voltage from a second external reference source; and

means for supplying a second current to the second terminal and, responsive to the second comparing means, for varying the second current to maintain the voltage at the second terminal substantially constant regardless of variations in the voltage of the negative energizing source; wherein

the first external reference source is negative; the second external reference source is positive; the first current supplying and varying means comprises:

a first operational amplifier having an input and an output, and

a first circuit connecting the output of the first operational amplifier to the second terminal of the binary-weighted resistor;

the first comparing means comprises:

a second circuit for connecting the input of the first operational amplifier to a negative reference source,

a third circuit connecting the input of the first operational amplifier to the second terminal of the binary-weighted resistor, and

means for disabling the first operational amplifier when the second terminal is connected by the second switching circuit to a negative energizing source;

the second current supplying and varying means comprises:

a second operational amplifier having an input and an output, and

a fourth circuit connecting the output of the second operational amplifier to the second terminal of the binary-weighted resistor; and

the second comparing means comprises:

a fifth circuit for connecting the output of the second operational amplifier to the positive reference source,

a sixth circuit connecting the input of the second operational amplifier to the second terminal of the binary-weighted resistor, and

means for disabling the second operational amplifier when the second terminal is connected by the first switching circuit to a positive energizing source.

4. A digital-to-analog converter according to claim 3 wherein the second circuit is a first resistor, the third circuit is a second resistor substantially equal in resistance to the first resistor, the fifth circuit is a third resistor, and the sixth circuit is a fourth resistor substantially equal in resistance to the third resistor.

5. A digital-to-analog converter according to claim 4 wherein said first and second switching circuits each include a series-connected resistor whose resistance is selected such that the sum of the resistance of the corresponding switching circuit and the internal impedance of the energizing voltage source connected thereto is substantially equal to the resistance of the associated binary-weighted resistor.
